UNITED STATES PATENT OFFICE.

JOHN W. PENDLETON, OF GREENVILLE, CALIFORNIA.

ADJUSTABLE THILL-COUPING.

SPECIFICATION forming part of Letters Patent No. 372,262, dated February 21, 1888.

Application filed July 9, 1887. Serial No. 243,828. (No model.)

To all whom it may concern:

Be it known that I, JOHN W. PENDLETON, of Greenville, in the county of Plumas and State of California, have invented a new and useful Improvement in Automatic Extension and Adjustable Thill-Couplings, which improvement is fully set forth in the following specification and accompanying drawings, in which—

- 10 Figure I is a top view of my invention showing thill-iron in place. Fig. II is a side view, partly in section; Fig. III, a view of the same, showing thill-iron in a changed position; Fig. IV, a perspective view of the members conjointly forming the yoke-socket; Fig. 15 V, a perspective view of the thill-iron adapted to the socket, and Fig. VI shows a rubber cushion to insert in the socket-recesses when desired to use an ordinary-shaped thill-iron.
- 20 The object of my invention is to provide a thill-coupling that will be convenient, secure, adjustable, and extensible, and serve as a thill-support when the vehicle is not in use, and which is also so arranged that the thill-iron, of any size or kind, can be readily and firmly attached or detached, all of which will now be fully set forth in detail.

Near each end of the axle and on the under side I provide a metallic plate, A, serrated 30 along its forward edge at A'. This plate is secured beneath and to the axle by means of ordinary clips, A', at each end. Upon this metallic plate or strip, which projects slightly from each side of the axle-bar, I provide a 35 pair of metallic members, B, which conjointly form the receptacle for the thill-iron. These metallic parts are provided with an undercut recess, C, so as to be slipped on the serrated plate or bar previous to the latter being secured by clips to the axle.

The forward ends of the metallic members are formed with segmentary recesses D, which receive and retain the corresponding segmentary flanges E, that are formed upon the thill-iron head F.

45 The rear end, G, of the thill-iron periphery has a hole which extends inwardly a suitable distance, in which is inserted a suitable pin, H, which bears outwardly. It is a retractile

pin having a beveled end. When the thill or 50 pole is raised to nearly its highest point, the pin H shoots out and locks itself against the inclined forward edge, J, of the socket sufficient to hold the shafts erect, but will retract itself with slight forcing and allow the thill to be 55 turned down for use.

The rearward peripheral face of the thill-iron comes against and secures in position a sliding dog, K, which extends through an aperture and engages with the serrated plate 60 A, so that when the thill-iron is secured in place the members B cannot be moved laterally.

It will be observed that this device is not only adjustable as to distance between the thill-irons, but each socket part is relatively 65 adjustable to accommodate any width of thill-iron, and as each part is provided with a sliding lock plug or dog it follows that each can be secured to suit any emergency.

The rubber cushion I, Fig. VI, is inserted 70 into the segmental cavities D, when it is desired to use an ordinary thill-iron, and the perforations provided in the parts B admit the use of the ordinary bolt which accompanies the eye in the ordinary thill-iron. 75

Having described my invention, what I claim, and desire to secure by Letters Patent, is—

1. In thill-couplings, the plate A, combined with the thill-iron holder B, recessed in the 80 forward end at D, and adapted to slide on said plate A, the dog K, the thill-iron, and the cushion I, substantially as described.

2. In thill-couplings, the plate on the under side of the axle projecting on the front and 85 rear sides, having its forward edge serrated, in combination with a bisected thill-iron holder having grooves which engage with the projecting axle-plate, and a dog, K, having a serrated edge in the cavity of the thill-iron 90 holder, substantially as herein set forth.

3. In a thill-coupling, the adjustable separable thill-iron holder having on its forward side a circular socket, the lower wall of which is inclined, in combination with a thill-iron 95 head provided with a rearwardly-projecting retractile pin having its lower end angled, substantially as herein set forth.

4. In a thill-coupling, the combination of an adjustable separable thill-iron holder and a serrated plate on the axle, said separable holder having in the rear wall of the socket a stud or pin, the rear end of which engages with the serrated plate, and the thill-iron head and rest-pin, substantially as herein set forth.

In testimony that I claim the foregoing I have hereunto set my hand, this 24th day of May, 1887, in the presence of witnesses.

JOHN W. PENDLETON.

Witnesses:

S. BORSINI,

THEODORE FORTINER.
